UNITED STATES PATENT OFFICE.

JOHN KRODER, OF NEW YORK, N. Y.

CURTAIN-FIXTURE.

No. 891,622.

Specification of Letters Patent.

Patented June 23, 1908.

Application filed January 29, 1908. Serial No. 413,162.

To all whom it may concern:

Be it known that I, JOHN KRODER, a citizen of the United States, and a resident of the city of New York, borough of Manhattan, in the county and State of New York, have invented a new and Improved Curtain-Fixture, of which the following is a full, clear, and exact description.

The invention relates to curtain holders for use on windows, doors, and the like, and its object is to provide a new and improved curtain fixture, formed of a split tube reinforced at each end by a rod in such a manner as to render the fixture comparatively light but exceedingly strong and convenient, for removable engagement with a socket or other support attached to the door, window, wall or the like.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a perspective view of the improvement; Fig. 2 is an enlarged sectional plan view showing one stage in the manufacture of the fixture; Fig. 3 is a plan view of the improvement, part being in section; Fig. 4 is an enlarged cross section of the improvement on the line 4—4 of Fig. 2; Fig. 5 is a perspective view of a modified form of the improvement, and Fig. 6 is a sectional plan view of the same.

The tube A for supporting the curtain is preferably made in split and telescoping sections A', A'', terminating at the outer ends in angular transverse arms A³, A⁴, for placing the front or main portion of the tube a desired distance from the wall, window, door or the like. The telescoping sections A', A'', permit of lengthening or shortening the fixture to suit the width of the door, window or the like.

The arms A³, A⁴, and adjacent portion of the main or front part of the tube A are reinforced by members B, inserted in the tube ends and either formed of solid rods as shown in Fig. 4, or in the form of tubes as illustrated in Figs. 5 and 6. The outer or projecting ends of the reinforcing members B terminate in attaching means for removable engagement with supports C, such as sockets or

brackets attached to the door, window, wall or the like, as indicated in Figs. 1 and 5. In case the reinforcing member B is in the form of a rod as shown in Figs. 1, 2, 3 and 4, then the outer end terminates in a downwardly-extending pin or offset B' for engagement with a support C in the form of a socket, as shown in Fig. 1, and in case the reinforcing member B is in the form of a tube as shown in Figs. 5 and 6, then the outer terminal is flattened and bent into an eye B² for engagement with the support C now in the form of a vertical pin on a screw screwing into the door, wall, window or the like.

If desired, the terminals of the arms A³, A⁴ may be extended to the outer terminals of the reinforcing tube and flattened and bent with the latter to reinforce the eye B², as shown in Figs. 5 and 6.

The end of each arm A³, A⁴ is engaged by a sleeve D, for closing up the split and for firmly clamping the tube onto the reinforcing member B adjacent to the pin B' or eye B².

From the foregoing it will be seen that the members B reinforce the bent ends of the tube A, and at the same time provide means for holding the tube in position on the supports C.

In manufacturing the fixture shown in Figs. 1, 2, 3 and 4, I proceed as follows: Each reinforcing and supporting member B is formed of a short, straight rod of wrought iron of a cross section corresponding to the inside of the tube section A' or A'', and this rod is first bent at one end to form the pin or offset B', and then the rod is inserted into one end of a straight tube, so that only the pin or offset B' projects at the end of the tube at right angles to the split of the tube (see Figs. 1 and 4). The tube with the rod therein is now bent by suitable means (hot or cold), to form the transverse arm A³ or A⁴, the rod within the tube serving as a mandrel for the tube, to allow of properly bending the same without breaking or indenting the tube. Now as the rod is bent with the tube it is held against removal from the tube, that is, the rod and the tube are firmly held one on the other. The sleeve D is next slipped in place on the end of the arm A³ or A⁴, to prevent the split of the tube from becoming open. Now by the arrangement described, the reinforcing rod extends a short distance in the main or front part of the tube and passes entirely through the arm A³ or A⁴, thus greatly reinforcing the tube without unduly increasing

the weight thereof. It will also be noticed that by the arrangement described the split of the tube is at the inside and hence not visible, and the split is not liable to open, as 5 it is closed at the end of each arm A³ or A⁴ by the sleeve D.

In manufacturing the fixture shown in Figs. 5 and 6, each reinforcing member B is in the form of a short, straight piece of pipe in- 10 serted into the tube section A' or A², and bent with the latter as before described. The terminals of the tube sections and reinforcing tubes are then flattened and bent to form the eyes B², as before explained.

15 Having thus described my invention, I claim as new and desire to secure by Letters Patent:

1. A curtain fixture, comprising a tube and reinforcing and supporting members for 20 the said tube, inserted in the ends thereof and bent with the latter to form angular arms, each reinforcing member projecting beyond the corresponding end of the tube for engagement with a support.

25 2. A curtain fixture, comprising a tube and reinforcing and supporting members for the said tube, inserted in the ends thereof and bent with the latter to form angular arms, each reinforcing member projecting beyond 30 the corresponding end of the tube, the projecting end of the said reinforcing member terminating in an attaching means for engagement with a support.

3. A curtain fixture, comprising a tube 35 and reinforcing and supporting rods for the said tube, inserted in the ends thereof and bent with the latter to form angular arms, each rod projecting beyond the corresponding end of the tube, the projecting ends of 40 the said rods terminating in downwardly-extending pins.

4. A curtain fixture, comprising a tube and reinforcing and supporting rods for the said tube, inserted in the ends thereof and 45 bent with the latter to form angular arms, each rod projecting beyond the corresponding end of the tube, the projecting end of the said rod terminating in an angular pin for engagement with a support, the said tube being

made in split telescoping sections, and sleeves 50 over the arm ends of the tube sections.

5. A curtain fixture, comprising a tube and reinforcing and supporting rods for the said tube, inserted in the ends thereof and bent with the latter to form angular arms, 55 each rod projecting beyond the corresponding end of the tube, the projecting end of the said rod terminating in an angular pin for engagement with a support, the said tube being made in split telescoping sections, and 60 sleeves over the arm ends of the tube sections, adjacent to the said pins.

6. A curtain fixture, comprising a tube and a supporting and reinforcing member for the same and terminating at its outer 65 end in an attaching means, the reinforcing portion of the said member being inserted in one end of the tube to form a mandrel for the same and to allow of bending the tube and its reinforcing member for forming a trans- 70 verse reinforced arm.

7. A curtain fixture, comprising a split tube and a supporting and reinforcing member terminating at its outer end in an attaching means, the reinforcing portion of the 75 said member being inserted in one end of the tube to form a mandrel for the same and to allow of bending the split tube and its reinforcing member for forming a transverse reinforced arm, and a sleeve over the terminal 80 of the split tube adjacent to the said attaching means.

8. A curtain fixture, comprising a split tube, a reinforcing member inserted in one end of the tube to form a mandrel for the 85 tube, to allow of bending the tube and reinforcing member, and a sleeve over the terminal of the tube to close the split end of the tube and to clamp the said tube end firmly onto the said reinforcing member.

In testimony whereof I have signed my name to this specification in the presence of two subscribing witnesses.

JOHN KRODER.
